PETER SCHNITZELER, OF BERLIN, AND AUGUST KAROLUS, OF LEIPZIG, GERMANY, AS-
SIGNORS TO RADIO CORPORATION OF AMERICA, A CORPORATION OF DELAWARE.

PICTURE RECORDING.

Application filed October 24, 1927, Serial No. 228,155, and in Germany October 29, 1926.

The present invention relates to recording apparatus for the transmission of pictures by radio or on wire circuits in which the recording of the incoming picture is effected 5 electro-chemically by virtue of the separation of suitable coloring ingredients by the aid of a current caused to pass through the recording surface which is rendered conductive.

10 The object of the present invention is to provide ways and means to record the incoming picture upon a continuously travelling picture strip or film so that the use of a complicated picture drum or cylinder may be dispensed with.

15 Other objects and advantages of this invention will be readily apparent from a reading of the specification in connection with the accompanying drawings, wherein;

20 Fig. 1, represents one form of roller adapted to our invention, and;

25 Fig. 2, is a modification of the showing of Fig. 1 wherein, the roller is provided with a thick layer of rubber in which the contact-

30 strip is placed.

For carrying out the above named objects, as shown in Fig. 1, a revolving cylinder 1 is employed. Upon the circumference of this cylinder a conducting edge 2 in spiral shape is secured. The conducting edge preferably forms one pole of the recording or reproducing device. The recording surface consists, for instance, of a strip or film of paper 3 soaked or impregnated with a suitable electrolyte. The film 3 is directed over a current-conducting straight edge 6 having the length of the metal cylinder. In the preferred embodiment of the invention the straight edge is arranged parallel to the metal cylinder 1

35 at the same height as the axis of the latter, and is so disposed that it bears with a slight amount of pressure against the spiral edge 2.

The straight edge parallel to the cylinder axis forms the second pole for the feed of the suitably amplified incoming current, which is so directed as to flow from the straight edge through the impregnated paper to the spiral edge. If, then, the said metallic cylinder is turned about its axis 4, the spiral edge 2 during each rotation rolls once at uniform rate of speed along the straight edge, or, in other words, the point of passage

of the current from one edge to the other edge is displaced uniformly over the entire width of the paper strip. If the latter is slowly fed forward, the spiral edge writes another line during the next rotation of the cylinder, and so on. Since separation of the coloring or inking electrolytic substance occurs only at the points where an incoming current happens to flow, the result is the picture to be transmitted.

One primary demand to be made of devices of this kind is that the pressure with which the straight edge and the spiral edge come to act upon the interposed paper or other writing material should be adequately high throughout, although the pressure should be nowhere unduly high, lest the paper between the two edges be ruptured or torn. However, in view of the varying thickness of the paper and of mechanical imperfections of the apparatus, the said requirement can never be fulfilled no matter how precise the workmanship. In order to insure sufficient contact pressure throughout, while avoiding excessive stressing of the inking material, according to another feature of the invention, as shown in Fig. 2, the spiral edge, which has suitably the form of a platinum wire 2', or of a wire of other strong and resistant material laid around the writing cylinder, is not brought upon a rigid cylindrical surface, but the said surface is made yielding and elastic. This is done most simply by subjecting the cylinder to a vulcanizing treatment, for example. In this case the cylinder 1' is coated with a sufficient thick layer of rubber 5. The wire 2' is there embedded in a shallow groove cut in said rubber layer, although the said groove may be dispensed with, provided the material possesses sufficient inherent softness. At such places where due to greater thickness of the writing or inking material or mechanical imperfections, undue pressure should arise, the elastic rubber layer is caused to yield, and the assembly is thus adjustable in such a way that good and yet yielding contact is insured throughout the entire line.

Having now described our invention what we claim is:

A picture inking apparatus adapted for electro-chemical recording or reproduction comprising, a rotary cylinder, a resilient

layer placed around said cylinder, a current-conducting edge spirally wrapped around said cylinder, said current-conducting edge resting upon said resilient surface, a second current-conducting edge extending adjacent and parallel said cylinder, and a paper strip between said spirally conducting edge and

said second current-conducting edge, said paper being adapted upon rotation of said cylinder to be moved forward, whereby variations in current are progressively recorded. 10
